Atlys

UNITED STATES PATENT OFFICE

CARL C. GROTNES, OF CHICAGO, ILLINOIS

METAL WORKING MACHINE

Application filed August 4, 1928. Serial No. 297,469.

The invention pertains to the art of making metallic drums, barrels, and similar articles, and has especial reference to an automatic machine for operating upon the opposite ends of cylinders employed in the construction of such articles. The invention has general reference to machines of the character shown in my prior Patent No. 1,604,345, dated October 26, 1926.

10 The object of this invention is to provide an improved machine of this character which is substantially automatic in character, in that after the operation of the machine has been manually started, the machine performs 15 a complete cycle of operative movements ending in the automatic discharge of the finished work therefrom and the stopping of the machine in position to receive a new piece of work.

20 Another object of the invention is to provide new and improved means for controlling the operation of the machine so that each piece of work will be uniformly finished.

25 A further object of the invention resides in the provision of an improved means for effecting the swinging movement of the upper forming roll into and out of engagement with the work piece including means for cushioning the upper roll at the end of a 30 swinging movement.

Other objects and advantages will become apparent from the following description and in the accompanying drawings in which:

Figure 1 is a side elevation of one end of 35 a machine embodying the features of the invention.

Fig. 2 is an end elevation of the end of the machine as shown in Fig. 1.

Fig. 3 is a fragmentary detail in elevation 40 of the rear side of the end of the machine shown in Fig. 1, parts thereof being broken away to show the automatic discharge.

Fig. 4 is a side elevation on a reduced scale showing the complete machine.

45 While the invention is susceptible of various modifications and alternative constructions, I have shown in the drawings and will herein describe in detail the preferred embodiment, but it is to be understood that I do not thereby intend to limit the invention

to the specific form disclosed, but intend to cover all modifications and alternative constructions falling within the spirit and scope of the invention as expressed in the appended claims.

55 Generally, as fully set forth in my aforementioned patent, the machine includes two sets of suitably driven forming rolls arranged to operate simultaneously upon the opposite ends of a cylindrical piece of work. The forming rolls are mounted for relative swinging movement to permit the work to be inserted in place therebetween, and guide means are provided to maintain the work piece properly in position between the rolls.

60 In attaining the objects of the invention, automatic control means is provided including a cam shaft carrying suitable cams for swinging the rolls to and from engagement with the work and for stopping the machine at a proper point in the operation thereof. In addition, cam means is provided for controlling the position of one of the guide rollers to effect the automatic discharge of a finished piece of work from the machine.

65 More particularly described, the machine comprises a bed or frame 5 supported upon suitable legs 6, and having journaled therein a main drive shaft 7, extending longitudinally of the bed. A pair of heads 8 of generally 70 similar construction are mounted upon opposite ends of the bed for relative endwise adjustment. Each head comprises a base portion 9, substantially in the form of a rectangular frame adapted to be secured to the bed, and an upper or swinging portion 10, pivotally mounted upon the base portion on transversely extending trunnions 11 journaled in the base portion. The upper swinging portion 10 has mounted therein a longitudinally 75 extending shaft 12 on which an upper forming roll 13 is rotatably mounted.

80 A spindle 14 journaled longitudinally of the base portion 9 of the head carries at its outer end a lower forming roll 15 arranged to coact with the upper forming roll upon the swinging head to provide complementary forming surfaces. For illustrative purposes, in the present embodiment, forming rolls capable of rolling flanges upon the ends of a 85

cylindrical work piece A are shown. Preferably the spindle 14 upon which the lower roll is mounted is driven from the drive shaft 7 through the gear train 16 and 17.

- 5 The upper rolls 13, being thus mounted for swinging movement toward the lower rolls to operate upon the work, and for swinging in the opposite direction to permit the finished work to be removed from the machine and a new piece of work positioned therein, are connected to similar control means provided in each head for automatically effecting their simultaneous movement in either direction. The control means for 10 each head in the present embodiment, comprises a cam member for moving the swinging frame downwardly to bring the upper roll into an abutting relation with the lower roll, and a second means associated with the cam member to effect a withdrawal or upward swinging movement of the frame at a proper time.

To this end a cam shaft 18 is journaled transversely of the base portion of the head at 25 a point positioned therein endwardly of the trunnions 11. The cam shaft is adapted to be driven from the main driving shaft in a suitable manner as by means of the gear train 19, 20 and 21 (Fig. 2) driving a shaft 22 which 30 carries a worm 23 arranged to engage a worm wheel 24 mounted upon one end of the cam shaft 18. A suitably shaped cam disk 25 (Fig. 1) is mounted upon the cam shaft 18 and is engaged by a cam follower, in the form 35 of a roller 26 suitably journaled upon the swinging frame 10. The cam is shaped to provide a rising actuating surface 27 which effects the downward swinging movement of the frame, a dwell surface 28 during the portion 40 of which the initial operation of rolling the work piece is accomplished, a second short rising surface 29, a second dwell surface 30 during which the finishing operating step is performed, and a trailing surface 31 which 45 permits the withdrawal or upward swinging movement of the frame.

Thus, the swinging frame will first be moved rapidly downward into initial engagement with the work piece by the rising surface 27 and will be held in that position while the first dwell surface 28 passes the follower, which operation forms the initial or breaking bend on the work piece. Preferably, the driven speed of the lower forming roll is such 50 that the work describes one complete revolution during the travel of the cam follower over the first dwell surface. Simultaneously with the completion of one revolution of the work, the second shorter rising surface 29 engages the follower to force the upper roll downwardly to perform the finishing operation upon the work, during which time the second dwell surface 30 engages the cam follower. The length of this surface is also pre- 55 determined so that the trailing surface 31

of the cam engages the follower to permit withdrawal of the upper roll from the work as soon as it has completed the prescribed number of revolutions. It will be seen therefore that each piece of work will be operated upon in precisely the same manner, thereby insuring the production of uniformly finished articles.

The means associated with the cam by which the swinging frame is swung upwardly to separate the forming rolls comprises an arm 32 pivoted to the swinging frame as at 70 33, and provided with a projecting portion or shoulder 34 arranged to be engaged by a projecting pin 35 carried on the side of the 75 cam. The disposition of parts is such that the engagement between the pin and the shoulder occurs immediately after the cam follower has moved from the second dwell surface 30 to the trailing surface 31. Disengagement of the shoulder 34 from the pin 35 80 may be effected in any suitable manner, as by providing a cam surface 36 on the arm 32 arranged to engage the edge of a slot 37 in a stationary bracket 38 through which the arm reciprocates, the cam surface 36 being disposed so that disengagement occurs substantially at the time the cam follower is between the rising and trailing surfaces on the 85 cam.

Manually operable means are provided for starting and stopping the operation of the machine, and the present invention contemplates provision of an automatic means for stopping the operation of the machine at a 90 predetermined point. Referring to Fig. 1, the main drive shaft 7 extends beyond one end of the bed of the machine and carries rotatably thereon a pulley 39 adapted to be driven from any suitable source of power 95 (not shown). A driving connection between the pulley and the drive shaft comprises a clutch member 40 of any generally well-known construction. A manual operating handle 41 rigidly mounted upon a rock shaft 100 42 journaled in the bed of the machine underlying one of the heads, is operatively connected to the clutch through intermediate linkage 43. Thus, movement of the handle in one direction or the other engages or disengages the clutch to start or stop the operation 105 of the machine.

The automatic stop means is actuated from the cam shaft 18 in the head overlying the rock shaft 42 and in the present instance comprises a vertically extending arm 110 44 pivoted intermediate its ends on the base portion of the head near the cam shaft. The upper end of the arm carries a pin 45 which, when the machine is in operation, projects 115 into the path of a cam finger 46 rigidly mounted upon the forward end of the cam shaft. The lower end of the arm is connected for actuation of the rock shaft 42 by suitable linkage 47. The finger 46 is so posi- 120 125 130

tioned on the cam shaft that the engagement of the finger with the pin 45 to swing the arm 44 and rock shaft 42 to disengage the clutch 40 occurs substantially at the time when the 5 swinging frame is in its most retarded position.

In the downward swinging movement of the swinging frame and upper roll, it is desirable to cushion or yieldingly resist the 10 movement of the upper roller into engagement with the work in order to prevent a too rapid engagement which might damage or break the forming rolls. Figs. 1 and 2 show such a means in the form of a pair of 15 helically coiled springs 48 mounted about upwardly projecting pins 49 secured upon the base portion of the head in such position that the springs extend upwardly to engage a portion of the lower surface on each 20 side of the swinging frame 10. Thus, as the frame swings downwardly the engagement between the frame and the springs yieldingly 25 resist the downward movement thereof.

The automatic discharge mechanism, by 25 which a finished piece of work is discharged from the machine as soon as the forming operations have been completed and the upper rolls have been moved out of engagement therewith, comprises, in the present instance, 30 cam controlled means for varying the position of the supporting means for the work piece in such manner that the work piece may move laterally out of the machine by gravity. In machines of this type it is customary 35 to provide a pair of supporting rollers 50, 51 on the base portion of each head and disposed relative to the forming rolls so as to support the work piece in proper position to be operated upon by the rolls. Referring 40 to Figs. 2 and 3, the opposing guide rolls 50 on the forward sides of the heads of the machine, are journalled in adjustable stationary supports 52 upon the base portions of the heads. The opposing rear guide rollers 45 51 are mounted on brackets 53 supported for sliding movement in vertically disposed ways 54 (Fig. 2) on the heads.

A suitable link 55, in both instances, connects the bracket with one end of a lever 56 pivoted to the base portion 9 as at 57, and the other end of the lever carries a cam roller 58 arranged to follow the surface of a cam 59 mounted upon the cam shaft 18. Rising and trailing surfaces 60, 61 are properly positioned on each of the cams 59 to effect a simultaneous downward movement of the guide rollers 51, and a subsequent upward movement thereof as soon as the swinging frames have moved upward a sufficient 60 distance to clear the ends of the work A. Guides or tracks 62 in the form of L-shaped members secured to the base portion of the frame, project outwardly therefrom to underlie the lower portion of each end of the 65 work in the machine and preferably slope

gently from the front to the rear of the machine. By this construction, as the rear guide rollers 51 move downwardly the guides 62 receive and support the work thereon until the rear guide rollers have been depressed 70 a sufficient distance to permit the work to roll from the machine.

In considering the cycle of operation of the machine, it is presumed that the drive shaft is idle and the swinging frames are 75 in their upward or retarded position, and a piece of work is supported upon the pairs of guide rollers 50 and 51. To start the operation in the machine, the lever 41 is manually moved to engage the clutch 40 and start 80 the drive shaft. This drives each cam shaft 18 and the engagement of the rising surfaces 10 downwardly to bring the upper rolls in 85 operative position relative to the lower rolls, the downward movement being cushioned by the springs 48. During this time the lower rolls have been driven through the gear trains 16, 17 and as soon as the upper rolls move into engagement with the work piece, the 90 work is caused to rotate therebetween and the breaking bend is formed thereon.

Preferably, as soon as one complete rotation of the work piece has occurred, the small rising surfaces 29 on the cams 25 further 95 depress the swinging frames to move the rolls into position for the finishing operation. A second complete revolution of the work piece follows after which the cam followers 100 on the swinging frames engage the trailing surfaces on the cams and the pins 35 on the cams engage the shoulders 34 on the arms 32 to move the swinging frames and the upper rolls out of engagement with the work. When the upper frames have moved to their retarded position the discharge control cams 59 move the rear guide rollers 51 downwardly to permit the work piece to roll from the machine. Immediately the rising surfaces 105 on the discharge control cams move the guide rollers upwardly into normal position after which the cam finger 46 on the cam shaft engages the pin on the stop arm 45 to rock the shaft 42 and disengage the clutch 40 thereby 110 stopping the drive shaft. Thus, a complete cycle of operation returns the machine to substantially the same point from which operation was started, insuring that each of the work pieces will be treated in precisely 115 the same manner and with the same uniformity.

I claim as my invention:

1. A metal working machine comprising, in combination, a bed, a pair of heads mounted in longitudinally spaced relation thereon and each having a forming roll rotatable on a fixed axis and a forming roll rotatable on an axis movable toward and from the fixed axis, a cam in each head operable upon the movable roll to move it toward the fixed roll, 125

- and means associated with said cam and operable at a predetermined point in the rotation thereof to retract said movable roll rapidly from said fixed roll.
5. 2. A metal working machine comprising, in combination, means for operating upon opposite ends of a drum or the like including two sets of forming rolls, one roll of each set mounted for rotation on a fixed axis and another mounted for rotation on a swinging axis, a cam shaft for each of the swinging rolls, a cam on each of said shafts operatively engaging said rolls to move the rolls in one direction, and positively engaging cam driven means for moving said rolls in the other direction.
10. 3. A metal working machine comprising, in combination, means for operating upon opposite ends of a drum or the like, including two sets of forming rolls, one roll of each set mounted for rotation on a fixed axis and another mounted for rotation on a swinging axis, a cam shaft for each of said swinging rolls, a cam on each of said shafts engaging the swinging rolls to effect a movement of said swinging rolls toward the stationary rolls, and means establishing a direct connection between said rolls and said shafts at a predetermined point in the rotation of each shaft to move said rolls away from the fixed rolls.
15. 4. A metal working machine comprising, in combination, a bed, a pair of heads mounted in longitudinal and spaced relation thereon and each having a forming roll rotatable on a fixed axis, a swinging frame on each of said heads, each having a forming roll journaled therein and capable of movement with said swinging frames into and out of operative association with said fixed rolls, a cam shaft for each of said swinging frames, cams on said shafts operatively engaging said swinging frames for movement thereof to swing the rolls together, means for cushioning the cam actuated movement of said frames, and means for moving the frames in the opposite direction.
20. 5. A metal working machine comprising, in combination, a bed, a pair of heads mounted in longitudinal and spaced relation thereon and each having a forming roll rotatable on a fixed axis, a swinging frame on each of said heads, each having a forming roll journaled therein and capable of movement with said swinging frames into and out of operative association with said fixed rolls, a cam shaft for each of said swinging frames, cams on said shafts operatively engaging said swinging frames for movement thereof to swing the rolls together, and a detachable engagement between said frame and said cam, engageable at a predetermined point in the movement of said cam to move said swinging frames in the opposite direction.
25. 6. A metal working machine comprising,
- in combination, a bed, a pair of heads mounted in longitudinal and spaced relation thereon and each having a forming roll rotatable on a fixed axis, a swinging frame on each of said heads, each having a forming roll journaled therein capable of movement with said swinging frames into and out of operative association with said fixed rolls, a cam shaft for each of said swinging frames, cams on said shafts operatively engaging said swinging frames for movement thereof to swing the rolls together, an actuating element rotating with each of said cams, arms on said frames extending in juxtaposed relation to said actuating elements, means providing an engagement between said elements and said arms at a predetermined point in the movement of said cams to effect a withdrawal of said swinging roll out of engagement with the fixed roll, and means for disengaging the arm from said elements upon further movement of said cams.
30. 7. A metal working machine of the character described, comprising, in combination, means for operating upon the end of a drum or the like including a set of forming rolls, one mounted for rotation on a fixed axis and another mounted for rotation on a swingable axis, means connected to the swingable roll for moving said roll into and out of operative association with the fixed roll, and means for cushioning the movement of said swingable roll in one direction.
35. 8. A metal working machine of the character described, comprising, in combination, means for operating upon the end of a drum or the like, including a set of forming rolls one mounted for rotation on a fixed axis and another mounted for rotation on a swingable axis, means connected to the swingable roll for moving said roll into and out of operative association with the fixed roll, and means engageable by the swinging roll in the movement thereof toward the fixed roll yieldingly to resist the movement of said swinging roll into operative association with the fixed roll.
40. 9. A metal working machine comprising, in combination, means for operating upon the opposite ends of a drum or the like, including two sets of forming rolls one roll of each set mounted for rotation on a fixed axis and another mounted for rotation on a swingable axis, means for driving one of said rolls, a clutch controlling said driving means, automatic control means operated from said driving means for moving said swinging roll into and out of operative association with said fixed roll, said control means including a trip mechanism operable when the swinging roll is in its remote position from said fixed roll to disengage said clutch.
45. 10. A metal working machine comprising, in combination, means for operating upon the opposite ends of a drum or the like, including two sets of forming rolls one roll of each set

mounted for rotation on a fixed axis and another mounted for rotation on a swingable axis, means for driving one of said rolls, a clutch controlling said driving means, a shaft operatively connected to said driving means, means on said shaft automatically controlling the swinging movement of said swinging roll, and means providing a connection between said shaft and said clutch operative at a predetermined position of said swinging roll to disengage said clutch.

11. A metal working machine, comprising, in combination, means for operating upon the opposite ends of a drum or the like, including two sets of forming rolls one roll of each set mounted for rotation on a fixed axis and another mounted for rotation on a swingable axis, automatic driving means connected to said swinging roll for initially moving said roll into operative engagement with the drum, and subsequently returning said roll to its initial position after completion of the forming operation, and means for discharging the drum from the machine after the 25 swinging roll has been moved out of engagement therewith.

12. A metal working machine comprising, in combination, means for operating upon the opposite ends of a drum or the like, including two sets of forming rolls one roll of each mounted for rotation on a fixed axis and another mounted for rotation on a swingable axis, an automatic control means including a driven shaft operable at predetermined 35 points in the operation of the machine to move said swinging roll into and out of operative engagement with the drum, said control means being further operable to effect the discharge of the work from the machine 40 when the swinging roll is out of engagement with the drum to stop the machine.

13. A metal working machine comprising, in combination, means for operating upon the opposite ends of a drum or the like, including two sets of forming rolls one roll of each set mounted for rotation on a fixed axis and another mounted for rotation on a swingable axis, means for supporting the work in position relative to said forming rolls, and 50 means automatically operable to move the work from said supporting means after completion of the forming operation.

14. A metal working machine comprising, in combination, means for operating upon the 55 opposite ends of a drum or the like, including two sets of forming rolls one roll of each set mounted for rotation on a fixed axis and another mounted for rotation on a swingable axis, a pair of guide rolls for each set of forming rolls arranged to support the work in position relative to said forming rolls, and means for lowering the opposing guide rolls in each set at a predetermined point in the operation of the machine to permit the work 60 to move from the machine.

15. A metal working machine, comprising, in combination, means for operating upon the opposite ends of a drum or the like, including two sets of forming rolls one roll of each set mounted for rotation on a fixed axis and another mounted for rotation on a swingable axis, a pair of opposed guide rolls for each set of forming rolls arranged to support work in position relative to said forming rolls, cam operated means for moving opposing rolls in each set to a remote position, and guiding means positioned adjacent said guiding rolls for receiving and directing the work out of the machine as said guiding rolls are moved to the remote position.

16. A metal working machine comprising, in combination, means for operating upon the opposite ends of a drum or the like, including two sets of forming rolls, one roll of each set mounted for rotation on a fixed axis and another for rotation on a swingable axis, means including a cam shaft for each of said sets of rolls operable to move said swinging rolls into and out of operable engagement with said fixed rolls, opposed guide rolls for each of said sets of forming rolls positioned properly to support the work relative to said forming rolls, and cams on said cam shafts, means operatively connecting opposing guide rolls with said cams, said cams being shaped to effect a withdrawal of the guide rolls connected therewith to a remote position when said swinging rolls are out of engagement with the fixed rolls to permit the work to roll from the machine.

17. In a metal working machine, in combination with a pair of forming rolls adapted to operate upon a drum or the like, a pair of guide rolls arranged to support the work in position between the forming rolls, means operable to move one of said guide rolls to a remote position and an inclined track underlying the guide rolls and supporting the work upon withdrawal of the guide rolls until withdrawal is complete.

18. A metal working machine combining means for operating upon opposite ends of a drum or the like including two sets of forming rolls, a swinging frame having one roll of each set journaled therein, another roll of each set mounted for rotation on a fixed axis, an arm pivoted to said frame and extending in the plane of rotation of said frame, a cam follower on said swinging frame, a cam engaging said follower to move said swinging frame into operative position, and a projecting pin on said cam engaging said arm to withdraw the swinging frame from operative position.

19. A metal working machine combining means for operating upon the opposite ends of a drum or the like including two sets of forming rolls, one roll of each set mounted for rotation on a fixed axis and another mounted for rotation on a swingable axis, a cam shaft

having a cam thereon, a cam follower swingable with the swinging roll and adapted to be engaged by said cam for movement of said swingable roll into position adjacent said fixed roll, and coacting means for rapidly withdrawing said swingable roll comprising, a spring tensioned by the movement of the swingable roll toward the fixed roll, and means operating at a predetermined point in the rotation of said shaft to effect movement of the swingable roll in the direction in which it is urged by said spring.

20. A metal working machine combining a bed, a head mounted thereon having a forming roll rotated on a fixed axis, a swinging frame on said head having a forming roll journaled therein capable of movement with said swinging frame into and out of operative association with said fixed roll, a cam engaging said frame for movement thereof to swing the roll into operative association with said fixed roll, an arm pivoted to said frame extending in juxtaposed relation to said cam, a bracket fixed to said head guiding said arm, 25 a pin rotating with said cam and engaging said arm at a predetermined point in the movement of said cam to effect a withdrawal of said swinging roll out of engagement with the fixed roll and a cam surface on said arm 30 engaging with said bracket to disengage the arm from said pin.

21. A metal working machine combining means for operating upon the ends of a drum or the like including a set of forming rolls, 35 a swinging frame having one roll of each set journaled therein, another roll of each set mounted for rotation on a fixed axis, a cam shaft for said frame, a cam on said shaft, an arm pivoted to said frame, means operable 40 with said cam for engaging said arm to effect withdrawal of said swinging roll from engagement with said fixed roll, means for releasing the engagement effecting withdrawal, and springs mounted on opposite 45 sides of the fixed roll to cushion the return movement of said swinging roll upon release of the engagement effecting withdrawal.

22. A metal working machine comprising, in combination, power actuated drive means 50 for operating upon the opposite ends of a drum or the like including two sets of forming rolls, one roll of each set mounted for rotation on a fixed axis and another mounted for rotation on a swingable axis, and means operable through positive connection with said drive means at predetermined points in the operation of the machine to move said swingable roll into and out of operative engagement with the drum.

60 23. A metal working machine comprising, in combination, means for operating upon the opposite ends of a drum or like including two sets of forming rolls, one roll of each set mounted for rotation on a fixed axis and another mounted for rotation on a swingable

axis, means for driving one of said rolls, a clutch controlling said driving means, means operatively connected to said driving means automatically controlling the swinging movement of said swingable rolls, and means operative at a predetermined position of said swingable roll to disengage said clutch.

70 24. A metal working machine comprising means for operating upon the end of a drum or the like including a set of forming rolls, 75 one mounted for rotation on a fixed axis and another mounted for rotation on a swingable axis, positive means for moving said swingable roll into operative position with respect to said fixed roll, positive means for retracting said swingable roll from such operative position, and a spring operative upon movement of said swingable roll into operative position to urge said roll in the direction of movement imparted by said retracting means 80 to accelerate such retraction.

85 In testimony whereof, I have hereunto affixed my signature.
